5 Claims. (Cl. 260—615)

It is known that orthoformic acid esters of lower alkanols can be re-esterified to form orthoesters of higher alkanols. In the simplest case, the orthoformic acid esters of the lower alkanol is boiled with the higher alkanol with reflux, so that the low alkanol that is released during the slow process of re-esterification is drawn off at the head. Re-esterification under the above conditions, however, is so slow that the process is uneconomical—it takes days to perform. The addition of sulfuric acid has been proposed for the purpose of accelerating this re-esterification reaction.

It has now been found that it is possible to manufacture esters of orthoformic acid with alkanols having 2 to 6 carbon atoms from orthoformic acid trimethyl ester with the avoidance of the above-described disadvantages, if orthoformic acid trimethyl ester is re-esterified in the liquid phase with alkanols having 2 to 6 carbon atoms, preferably 2 to 4 carbon atoms, in the presence of 0.01 to 1 weight-percent, and preferably 0.04 to 0.6 weight-percent, of formic acid. The percentage of formic acid added is based on the total amount of the reactants.

In the re-esterification of the invention, the re-esterification equilibrium is established within a short time. Then the released low alkanol can be removed by distillation from the equilibrium and, by the repeated addition of formic acid, in the same quantity range, and in the same time, the state of equilibrium corresponding to the existing composition can be adjusted, whereupon the percentage of the triester of the higher alkanol increases in such a manner that separation of the starting ester and the intermediate esters by distillation is economical.

An elevated temperature can be used. For example, the reactants can be heated to any temperature up to the boiling point of the mixture. It is desirable, however, to employ room temperature for the reaction. The reactants can be left at room temperature until the new equilibrium for the reactants is established. This will commonly require a period of hours, for example 1-3 hours.

The process of the invention can also be performed continuously, if desired.

The alkanols, the starting ester and the intermediate esters are removed at the top, while the desired triester remains in the sump of the column. The head product can then be fed back into the process at an appropriate point.

The advantages of the addition of formic acid to the reaction mixture consist in the fact that simple formic acid esters are formed, which correspond to the amount of formic acid added, and which do not interfere with the process and do not harm in the end product, depending on the application for which it is intended, or which otherwise can be separated without difficulty by distillation, on account of their low boiling point.

Example 1

Equivalent amounts of orthoformic acid trimethyl ester (106 grams) and ethanol (138 grams) are combined with 0.12 gram of formic acid and thoroughly mixed together until homogeneous. After two hours the re-esterification

2

equilibrium has established itself. The mixture then contains orthoformic acid triethyl ester, orthoformic acid diethyl monomethyl ester, orthoformic acid monoethyl dimethyl ester, orthoformic acid trimethyl ester, methanol and ethanol. By continual distillation, most of the liberated methanol is separated. By adding the same amount of formic acid to the cooled mixture in the sump, the equilibrium corresponding to this composition of the starting mixture is established within a short time (1 to 2 hours).

10 Next the newly formed methanol is distilled off. Then, by a second distillation, the orthoformic acid triethyl ester is separated from the intermediate esters and the orthoformic acid trimethyl ester still present, as well as from the remaining ethanol. The orthoformic acid triethyl ester 15 has the highest boiling point of the above-named components. It remains in the sump and can there be drawn off. The yield amounts, with reference to the starting quantity, (to 60 to 75 grams) (40% to 50%, with reference to the theory). The head mixture driven off in this 20 stage can be circulated in such a manner that it is added to a new batch after the first distillation, so that the total yield, as the operation continues, amounts to more than 95% of the theory, with reference to the orthoformic acid trimethyl ester that was put in.

Example 2

Orthoformic acid triisopropyl ester:

636 grams of orthoformic acid trimethyl ester are thoroughly mixed with 1200 grams of isopropanol and about 30 4 to 5 grams of formic acid. An efficient distillation column equipped with a reflux divider is placed upon the reaction vessel and most of the methanol is distilled away at a reflux ratio of 1:10. The excess isopropanol is removed in like manner. Rectifying the remainder produces 35 800 to 880 grams (70 to 77% of the theory) of orthoformic acid triisopropyl ester.

Example 3

Orthoformic acid tributyl ester:

530 grams of orthoformic acid trimethyl ester, 1220 grams of n-butanol and 4.5 grams of formic acid are thoroughly mixed and, as described in Example 2, methanol is first removed at a refluxing ratio of 1:10 and then most of the excess butanol is removed at a refluxing ratio of 1:5. Fractionation of the remainder at 10 Torr produces about 1060 grams (91% of the theory) of orthoformic acid tributyl ester.

Example 4

Orthoformic acid trihexyl ester:

In a manner similar to Examples 3 and 4, 1260 grams (80% of the theory) of orthoformic acid trihexyl ester can be produced from 530 g. of trimethyl orthoformate and 1680 g. of n-hexanol with the addition of about 0.2% formic acid.

Example 5

Orthoformic acid tripropyl ester:

Equivalent quantities of trimethyl orthoformate and n-propanol are thoroughly mixed with 0.06% formic acid. 60 The ester equilibrium is established at room temperature in about 1 to 2 hours. This mixture is then fed to the center of a continuously operating first fractional distillation column. At a reflux ratio of about 1:15, a methanol of high purity is taken from the head of the column. The sump product of the column, which contains about 50% tripropyl orthoformate, is continuously fed to the center of a second fractional distillation column where, at about 200 Torr, a refluxing ratio of about 1:4, a sump temperature of 155° C., and a head temperature of 115° C., orthoformic acid tripropyl ester is taken from the sump. The head product contains mainly n-propanol, the intermediate esters and tripropyl orthoformate, plus a little methanol.

This mixture is fed back to the first column together with the starting materials. In this manner, yields of more than 95% of the theory are obtained of tripropyl orthoformate.

What is claimed is:

1. Process for the manufacture of a triester of ortho-formic acid and an alkanol having 2-6 carbon atoms by liquid phase reaction which comprises contacting ortho-formic acid trimethyl ester with an alkanol having 2-6 carbon atoms in the presence of 0.01-1 wt. percent of formic acid based on the total amount of the reactants, at a temperature and for a time sufficient for formation in said liquid phase of said triester of orthoformic acid and alkanol containing 2-6 carbon atoms, methyl alcohol, and esters of said formic acid, and separating methyl alcohol and said esters of formic acid from said liquid phase by distillation.
2. Process according to claim 1, wherein the monoester and diester of orthoformic acid and said alkanol having 2-6 carbon atoms formed during said contacting by reaction of said trimethyl ester and said alkanol having 2-6 carbon atoms, are removed by distillation carried out

subsequent to the removal of methyl alcohol by distillation.

3. Process according to claim 1, wherein the alkanol contains 2-4 carbon atoms and said formic acid is used in amount of 0.04-0.6 wt. percent.

4. Process according to claim 1, wherein said alkanol is ethanol, isopropanol, n-butanol, or n-hexanol.

5. Process according to claim 1, wherein said alkanol is ethanol.
